(57) **CLAIM**

The ornamental design for a vehicle front upper bumper cover, as shown and described.

DESCRIPTION

FIG. 1 is a front elevational view of a vehicle front upper bumper cover, showing our new design;

FIG. 2 is a left side elevational view thereof;

FIG. 3 is a right side elevational view thereof;

FIG. 4 is a top plan view thereof;

FIG. 5 is a bottom plan view thereof;

FIG. 6 is a top, front, and left side perspective view thereof; and,

FIG. 7 is a bottom, front, and left side perspective view thereof.

Any broken lines represent boundaries of the design; the line itself and the area within, or outside the boundary form no part of the claim.
